UNITED STATES PATENT OFFICE.

EMIL BIER, OF MÜLHEIM-ON-THE-RUHR, AND ADOLF HOFFMANN, OF COLOGNE, GERMANY.

PROCESS OF PRODUCING SOLID DRAWN TUBES.

No. 831,031.

Specification of Letters Patent.

Patented Sept. 18, 1906.

Application filed December 22, 1905. Serial No. 292,987.

To all whom it may concern:

Be it known that we, EMIL BIER, residing at Mülheim-on-the-Ruhr, and ADOLF HOFFMANN, residing at Cologne, in the Province of the Rhine, Kingdom of Prussia, German Empire, subjects of the King of Prussia, German Emperor, have invented a new and useful Process for Producing Solid Drawn Tubes, of which the following is a specification.

10 The processes hitherto in use for the preparation of hollow blocks such as are used in industry especially for the purpose of rolling out and in the construction of seamless tubes and boiler-making are very complicated and costly. In general this operation has hitherto been effected by removing by mechanical means the upper end of the cast block, which contains air-holes and flaws after it has cooled, then again heating the block and 15 driving the mandrel through it by means of a press.

20 The new process for the production of solid annular cast blocks depends in principle on the circumstance that the material cast in a mold tapering upward receives from its lower annular surface an upwardly-directed pressure and is moved upwardly, while at the same time a tapering mandrel in the interior of the block, though compelled to follow the upward motion, receives a pressure from above in the direction opposite to the pressure acting upon the lower annular surface of the block which imparts to it a retrograde motion—that is to say, while 25 the block is pressed up in the tapering mold for a certain height the mandrel rises to a lesser height. By this means the following advantage is obtained: The pressure exercised by the tapering wall of the mold upon 30 the material while being raised compresses the latter to a high degree of density, and being transferred also upon the mandrel this latter is caused by friction to participate in the upward motion of the material. The 35 shrinking of the block would lead to a splitting of the same; but this is prevented by the retrograde motion caused, as stated, by a pressure from above upon the mandrel. This motion is regulated specially in each particular case according to the strength of the 40 block and its shrinking, so as to prevent any splitting of the cooling block.

45 Figure 1 of the accompanying drawings illustrates by way of example, partly in ele-

5 vation and partly in section, a press which can be utilized for the carrying out of the process above set forth. Fig. 2 is a similar view showing the parts in elevated position. Fig. 3 is a diagram illustrating, respectively, the rising motions of the metal block and of 60 the mandrel, the curves indicating how much the latter is gradually falling back.

In the drawings, *a* denotes the lower piston; *b*, the upper piston; *c*, the mold tapering upward, with a cylindrical part of the 65 height *d* at its lower end. In the interior of the mold there is placed the tapering mandrel *e*, which is seated upon a thin sheet-metal disk *f* of exactly the same diameter as the cylindrical part of the mold. A loose 70 piston *l* above piston *a*, filling this cylindrical part, is recessed at its upper face and counterbored centrally to receive the lower tenon of the mandrel. By this means a closure against the material *g* is provided 75 when it is poured in from above, and the retrograde motion *h* is assured, as the mandrel can recede into the recess of piston *l* by shearing off the middle part of disk *f*. The mold *c* rests upon a ring *i* and this in turn 80 upon a carriage *k*, which latter holds the piston *l*, supporting the disk *f*.

The press is shown in its initial position in the illustration, Fig. 1. The material *g* has been poured. The piston *b* has been lowered, 85 together with a plate *m*, upon the tapering mandrel *e*. As soon as the liquid material commences to harden hydraulic pressure is applied to both the pistons *a* and *b* through the tubes *n* and *o*, whereby the following effect is attained: The lower piston *a* reaches the piston *l* and carries it upward. This latter presses by means of its annular upper part upon the disk *f*, which conveys the pressure to the material in the mold. The upper 90 piston *b* acts upon the tapering mandrel. By means of the pressure exercised by the annular part of piston *l* the material is forced upward in tapering shape. The walls of the mold exercise pressure upon the material, imparting to it a high degree of density. The tapering mandrel is caused to take part in the upward motion, being held fast by the shrinkage of the material while cooling. This reaction, in case the mandrel rose in the same degree as the piston *l*, would cause a splitting 95 of the material as it cooled further; but this accident is prevented by the retrograde mo-

tion of the mandrel imparted by the upper piston, which as it is smaller than the lower one, is at first compelled to rise, but by closing up the opening σ the pressure liquid being 5 hind piston b is gradually compressed and piston b is compelled to recede or fall back. It is easy to control the apparatus so as to regulate the motion of the pistons according to the extent of the shrinking. Fig. 2 shows 10 the press after the completion of the process. The piston l has traveled the distance $p x$. The upper piston has traveled the distance $p h$. The disk f has been sheared off in the motion. The hollow block g is finished. The 15 pressure fluid is then allowed to escape from the tube n , the pistons a and l return to their original position, the upper piston is pressed downward, and in its further course the plate m encounters the finished block and pushes 20 it out. The strokes of the pistons a and b are different for each block and are determined graphically by means of curves. In Fig. 3 are 25 shown two pairs of curves belonging to two different blocks. A or A' is the curve of the piston a . B or B' is the curve of the piston b . Further, s denotes the stroke of the piston, and t the time within which the process is completed. It will be seen from the curves 30 without further explanation that the distance x represents the retrograde motion.

The motions of the piston are transferred by means of a suitable indicating device upon the predetermined curves which form the control diagram. According to these curves 3 the control must be conducted, and thus one has at any time an illustration of the condition of the process. By cooling the mandrel and the mold the duration of the process can be shortened as much as desired. The distance t will then be correspondingly reduced.

Having thus described our invention, what we claim is—

Process for the production of highly-densified hollow metal blocks or ingots which consists in casting the metal into a tapering mold around a tapering mandrel or core of taper of higher degree, then allowing the metal to solidify, then pressing the ingot axially into the taper mold together with the taper mandrel to increase the density, allowing the mandrel to retrograde during the motion, substantially as described and for the purpose set forth.

In testimony whereof we have signed our names to this specification in the presence of two subscribing witnesses

EMIL BIER.

ADOLF HOFFMANN.
